US00D346246S

United States Patent [19]

Barreto et al.

[11] Patent Number: Des. 346,246

[45] Date of Patent: ** Apr. 19, 1994

[54] PET BED

[76] Inventors: Aurelio F. Barreto; Darrell R. Paxman, both of 303 Parkplace, Suite 132, Kirkland, Wash. 98033

[**] Term: 14 Years

[21] Appl. No.: 2,107

[22] Filed: Dec. 2, 1992

[52] U.S. Cl. D30/118

[58] Field of Search 119/28.5, 17, 19, 27-28, 119/165-170, 61; D7/550-552, 698; D9/328; 5/12.1, 42.4, 53.1, 94, 400-401, 449, 902; D6/601, 604, 390, 382, 393, 333-335; D30/108-109, 117-120, 133, 161
